JEWELRY

Michael Chernow, New York, N. Y.

Application March 12, 1941, Serial No. 382,889

3 Claims. (Cl. 40—142)

The present invention relates to initial jewelry and is applicable to men's, women's and children's jewelry generally, including cuff links, tie clasps, fobs, stick pins, finger rings, key chains, earrings, bracelets, brooches, clips, badges and the like.

It is among the objects of the invention to provide an article of jewelry in which stamped initial units selected from stock by the purchaser may be almost instantly applied securely by the sales person to the face plate thereof, to produce a finished piece which does not appear to have been assembled from inexpensive stampings, but which has the earmarks of a costly piece, the initials on which appear to be an integral part of a plate made to order.

Another object is to provide a simple and expeditious method of fabricating initial units in mass production with unitary fastening means which, except for the original cost of dies, involves but small expense for metal stock of standard gauge and practically negligible expense for workmanship.

In the accompanying drawing in which is shown one of various possible embodiments of the several features of this invention,

Fig. 1 is a perspective view of rod stock from which the initials may be made.

Fig. 2 is a view in longitudinal cross-section showing the swaging operation for making the initials,

Fig. 3 is a rear perspective view of one of the initial units immediately after it has been swaged out,

Fig. 4 is a perspective view showing the process of milling the lug to form the mounting prongs,

Fig. 5 is a perspective view similar to Fig. 3 of the completed initial unit,

Fig. 6 is a plan view of a jewelry face plate to which the initial is to be applied,

Fig. 7 is a view similar to Fig. 6 showing the face plate with the initials in place thereon,

Fig. 8 is a view in longitudinal cross-section taken on the line 8—8 of Fig. 7 and on a larger scale, indicating the method of affixing the initial unit in place upon the article of jewelry,

Fig. 9 is a view in longitudinal cross-section taken on the line 9—9 of Fig. 7 and on a larger scale of the completely assembled article and

Fig. 10 is a rear plan view of a portion of the assembled article.

Referring now to the drawing, there is illustratively shown in Figs. 6 and 7, the face plate 11 of an article of jewelry such as a cuff link, tie

clasp, fob, pendant, brooch, badge or the like, which is provided with apertures 12 at which are to be secured the mounting prongs of the respective initials. It is desirable to provide initial units 13 each provided with unitary or integral prongs 14 protruding from near the middle of the rear face thereof. In the specific embodiment shown, the initial unit is made of fairly soft metal which in the precious embodiment may be of gold, platinum or silver alloy and in the usual less costly embodiments may be of gold plated soft brass. The prongs have an enveloping perimeter corresponding to the aperture 12.

In the specific embodiment shown, the initials 15 are of generally square contour and the mounting apertures in the face plate have their edges parallel to the rim of the face plate. Illustratively the prongs 14 are shown as of width in the order of $\frac{1}{16}$ inch, and parallel to each other, with their outer faces spaced by a like distance of $\frac{1}{16}$ inch. The extremities of the prongs are shown rounded as at 15.

The initial units, selected as desired, are positioned upon the face plate 11 to cause the prongs 25 14 to penetrate through the aperture 12 into which they will fit fairly snugly, with the outer faces of the prongs engaging opposite parallel edges along the length of the square aperture and the lateral edges of the prongs engaging the 30 connecting parallel edges along the width of the aperture.

The prongs 14 are preferably of length no greater than the thickness of the face plate 11 but the rear face of the latter is countersunk 35 preferably as a circular depression 16 immediately about the square aperture 12 to accommodate the extremities of the prongs, so that they will not protrude from the plane of such rear face. Desirably, the extremities 17 of the prongs

40 14 are deformed outward for securing the initial in position. Such deformation may be effected by resort to a wedging tool 18 having one jaw 19 with a leather face 20 to engage the face of the initial 13 and the other jaw with a conical die

45 21 to be introduced between the prongs 14, so that upon exerting pressure, the prongs will be deformed and spread as best shown in Fig. 10 to cause the median portion thereof to be curved or flared outward from its rounded edge as at 22 50 under the edge of the aperture 14, thereby securely to affix the respective initials in position.

It is preferred, as best shown in Figs. 6, 7 and 9 to provide the face plate 11 with an upstanding rim 23 parallel to and spaced from the square aperture 12 at a distance such that two of the

edges of the initial will snugly engage the inner wall of the rim 23, to contribute to the secure keying of the initial in place and to the finished appearance of the completely assembled article. In the illustrative embodiment shown, the face plate 11 is illustratively provided with transverse unitary bands 24 rising therefrom, the end of which will also engage the corresponding corner 13' of the initial 13 to assist further in keying the same in place, and in contributing to the attractiveness of the design.

In the particular embodiment disclosed, the main area of the face plate is shown roughened as at 25 and the polished initials rise therefrom as shown. The appearance of the finished article is that of an integral costly hand worked unit, which does not afford any suggestion that it has been assembled from inexpensive stamped elements as above set forth.

While the initial units may be fabricated in any of various ways, a simple, inexpensive and expeditious mode of manufacture is herein disclosed and claimed. The initials are desirably stamped from rod stock R shown in Fig. 1 as of generally oval cross-section. The die diagrammatically shown in Fig. 2, of the shape of the initial to be made, has a square opening 28 through its base, so that, when the relatively soft metal stock is forced into the die by plunger 29 in the swaging operation, the metal is deformed to the shape shown in Fig. 3, where the character proper appears at 30 with its outline, illustratively shown as the letter H, and where the excess stock that had been forced into aperture 28 of the die is the generally square block 31 of about $\frac{1}{16}$ inch across, protruding as a unitary integral part of the initial from the middle of the rear face thereof. The outer face of said block 31 will be rounded as at 32, corresponding to the round conformation of the original unformed oval stock.

To bifurcate the block 31 in order to form the two prongs 14 the jig shown in Fig. 4 is desirably provided, affording a track 33 for the initials proper which may be readily fed into position therein, wholly regardless which of the four sides of the generally square perimeter thereof is at the entry end. The upstanding ledges 34 of the jig are spaced by the width of the blocks 31, the sides of which are thus engaged thereby as shown. A milling cutter 35 appropriately placed and of suitable width, in the order of a $\frac{1}{2}$ inch wide, now mills out the central portions of the blocks 31, removing the material thereof clear down to the rear plane of the initial face 11, whereby the block is bifurcated into the two unitary prongs 14 shown in Fig. 5.

It will be apparent that regardless whether the widths of the prongs happen in the finished initial to extend along the height of the initials or along the width thereof, the assembly is exactly the same, because by reason of the generally square conformation of the initials, the prongs whether extending along the height of the plate or along its width when assembled, will be flared in exactly the same way by the introduction of the conical die 21 as above described.

It will of course be understood that while it is

preferred to apply the invention to the geometrically similar and specifically the square conformation of face plate, initial and mounting aperture as set forth, the broader claims embrace within their scope face plates, initials and apertures, any or all of which are of other shape, in fact of any contour, angular or curved.

While the jewelry has been designated in the claims as initial jewelry and finds its greatest field of application in that use, it will of course be understood that any emblems, decorative or symbolic might be substituted for the initials, and yet come within the scope of the claims.

It is also apparent that the face plate to which the initials are applied need not be an article of jewelry in the ordinary sense of the term, but may be an escutcheon or face plate for luggage, wallets, golf bags, cigarette cases, furniture and other articles.

As many changes could be made in the above article and method and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent is:

1. Initial jewelry comprising a face plate having a square aperture therethrough, a metal initial having unitary mounting prongs protruding from the rear face thereof, of width equal to the length of said square aperture, and with the outer faces thereof spaced by the width of said aperture, the protruding extremities of said prongs being flared outward along their longitudinal mid-sections for anchoring engagement with the plate.

2. The combination recited in claim 1 in which the prongs are of length no greater than the thickness of the face plate and the rear face of said plate is countersunk about the square aperture to accommodate the flared ends of the prongs.

3. Initial jewelry comprising a square face plate having an upstanding rim, square apertures located along a diagonal of said plate and with sides parallel to those of said rim, square soft metal initials, each equipped with a pair of mounting prongs integral therewith near the middle of the initials, the width of said mounting prongs extending parallel to the sides of said initials and being substantially equal to that of said square apertures, the outer faces thereof being spaced substantially by the width of said square aperture, the prongs of each initial fitting relatively snugly into the corresponding square aperture, and the initials being of dimensions such that a pair of adjacent edges thereof engage the inner wall of said rim, said prongs being of length no greater than the thickness of the plate, the apertures through the plate being enlarged at the rear face thereof to accommodate the outturned extremities of said prongs.

MICHAEL CHERNOW.
